D15-73.

OR D14-334

EX

Design No. 14,334, dated October 2, 1883.

UNITED STATES PATENT OFFICE.

WILLIAM HAEHNEL, OF NEW YORK, N. Y., ASSIGNOR TO CHARLES PALM,
JULIUS FECHTELER, AND CASPER FECHTELER, ALL OF SAME PLACE.

DESIGN FOR ORNAMENTATION OF SEWING-MACHINES.

SPECIFICATION forming part of Design No. 14,334, dated October 2, 1883.

Application filed August 15, 1883. Term of patent 7 years.

To all whom it may concern:

Be it known that I, WILLIAM HAEHNEL, of the city of New York, and county and State of New York, have invented and produced a new and original Design for the Ornamentation of Sewing-Machines, of which the following is a specification.

This invention relates to a new and original design for the ornamentation of sewing-machines and other articles; and it consists in the novel grouping and configuration of figures, hereinafter more fully described.

The accompanying illustration shows in Figures 1 and 2 opposite views of a sewing-machine plate and arm having thereon my new design. Fig. 3 is an enlarged side view of the sewing-machine arm; Fig. 4, an enlarged side view of the opposite side of the arm; Fig. 5, a front view of the same, and Fig. 6, a top view of the cloth-plate ornamented according to this invention.

The standard of the sewing-machine arm is ornamented on each side by figure A, which is a curving vine, bearing oak-like leaves on its lower part and a series of buds at its upper part.

Each side of the arm proper is ornamented by the figure B, which is composed in its center of two crossing twigs bearing small rose-sette-like flowers, and at its ends of curving vines bearing leaves of peculiar outline. At the ends of these curving vines are undulating dashes, which add to the striking effect of the ornamentation.

The front end of the sewing-machine arm is ornamented by the figure C, which is more fully shown in Fig. 5, and which is composed of several branches of leaves, some of the branches bearing oak-like leaves, others leaves apparently in bud and grain-like clusters of fruit, all as shown in Fig. 5.

The sides of the needle-arm are ornamented by the small figures D D, which are curving vines bearing bud-like leaves, as shown.

The front of the cloth-plate is ornamented by the figure E, which is a double curving vine, bearing in its middle portion oak-like leaves and toward its ends smaller bud-like leaves, as shown in Fig. 6.

At the sides the cloth-plate is ornamented by the figures H, which are also curving vines bearing leaves of the kind already described.

I claim—

1. The design for the ornamentation of sewing-machines, consisting of the figure A, as shown.

2. The design for the ornamentation of sewing-machines, consisting of the figure B, as shown.

3. The design for the ornamentation of sewing-machines, consisting of the figure C, as shown.

4. The design for the ornamentation of sewing-machines, consisting of the figure D, as shown.

5. The design for the ornamentation of sewing-machines, consisting of the figure E, as shown.

6. The design for the ornamentation of sewing-machines, consisting of the figure H, as shown.

7. The design for the ornamentation of sewing-machines, consisting of the figures A B, as shown.

8. The design for the ornamentation of sewing-machines, consisting of the figures A, B, and D, as shown.

9. The design for the ornamentation of sewing-machines, consisting of the figures E and H, as shown.

10. The design for the ornamentation of sewing-machines, consisting of the figures A, B, C, D, E, and H, as shown.

WILLIAM HAEHNEL.
